UNITED STATES PATENT OFFICE.

CECIL W. STANCLIFFE, OF NEW YORK, N. Y., ASSIGNOR TO STANCLIFFE ENGINEERING CORPORATION, OF NEW YORK, N. Y., A CORPORATION OF NEW YORK.

ISOTHERMAL AIR COMPRESSOR.

Application filed August 24, 1923. Serial No. 659,074.

To all whom it may concern:

Be it known that I, CECIL W. STANCLIFFE, a subject of the King of Great Britain, residing at New York, in the county of New York and State of New York, have invented new and useful Improvements in Isothermal Air Compressors, of which the following is a specification.

The purpose of this invention is to produce a machine adapted to compress air and other gases to whatever pressure may be desired, and at the same time to abstract the heat of compression from the air as fast, or nearly as fast, as developed, to the end that the temperature of the compressed air will be substantially as low as that of the air before compression, or at least not greatly higher, and substantially the full benefit of the work done in compressing the air will be retained and will not be subject to dissipation by loss of pressure through subsequent cooling of the air.

In air compressors as heretofore used, it has been the custom to cool the compression cylinders by means of water, in order both to prevent too high a temperature being developed and to cool the air before compression; and in the practice of plural stage compression, it has been customary to cool the air additionally between the successive stages. Such cooling, however, does not secure isothermal compression or any result nearly approximating the maintenance of uniform temperature, nor prevent the temperature of the air at the end of the compression mounting to a very high degree.

The particular purpose and accomplishment of this invention are to bring the cooling medium into such close and intimate thermal contact with the air being compressed and to divide the air in course of compression into such small films in such contact with cooled enclosing walls, that no substantial rise of temperature, due to compression, can take place in the air and the pressure may be raised to any desired degree in a single stage of compression.

In the following specification I have described one of the forms of compressor embodying my invention by which the desired results are obtained, and in the accompanying drawing I have illustrated the compressor so described.

In the drawings,—

Figure 1 is principally a longitudinal section and partly a side elevation of the air compressor referred to. 55

Figure 2 is partly a cross section and partly an end elevation as seen from the left of Figure 1 of said compressor. 60

Figure 3 is a fragmentary sectional view showing one of the compression plungers at the end of its compressing stroke.

Like reference characters designate the same parts wherever they occur in all the figures. 65

In the drawings *a* represents a heat interchanger comprising a substantially solid block of heat-conducting material having a number of rows of passages *b*, *b*, *b* extending in parallel in one direction, and a second set of passages *c* extending parallel to one another in a different direction and arranged in rows between the rows of passages *b*. Such a heat interchanger is disclosed in my prior application filed August 7, 1922, Serial No. 580,073, and it may be constructed as therein set forth. 70

Secured to one end of the unit *a* is a chamber, preferably a cylinder *d*, the axis of which is parallel with the axes of the passages *c*; and secured to the opposite end of the unit is a fitting *e* which encloses a chamber *f* in communication with the passages *c*. This fitting has an inlet valve *g* through which air may be drawn into the chamber, passages and cylinder, and it has also an outlet valve *h* through which the compressed air may be expelled. These valves are represented as being self-closing 85 against the flow of air in the opposite direction to that in which the air is designed to flow. 90

Over the intermediate faces of the unit *a*, through which the passages *b* open, are mounted and secured fittings *i* and *j* having connections to receive and carry away respectively a cooling fluid, such as water, or any other fluid which normally has, or to which may be given, a temperature low 100 enough for the purpose in view.

A piston *k* works in the cylinder *d* and is driven by a piston rod *l* by any suitable means. Although the showing of the piston and its relation to the cylinder is diagrammatic in nature for the purpose of illustration, it is to be understood that this piston will be properly made and adequately

packed to prevent appreciable leakage of the air when compressed to the required pressure.

Plungers p are connected to the piston k and are equal in number to the passages c , each plunger being alined with one of the passages and adapted to move back and forth therein. These plungers do not fit the passages but are preferably enough 10 smaller to permit free flow of air into the passages from the cylinder space while the compression stroke is in progress. Also the plungers are tapered with the large end of the plunger next to the piston. In other 15 words, the arrangement of the plungers is such that the clearance between them and the walls of the passages is at the minimum when the compression stroke ends.

It will be readily apparent that during 20 the intake stroke of the piston air is drawn through the passages c into the cylinder d and is more or less cooled by contact with the walls of the passages, these walls being maintained at a low temperature by the 25 cooling fluid which passes through the passages b and keeps the entire block a at a low temperature. During the compression stroke the volume of air in the cylinder is forced through the passages c , and as the 30 total capacity of all the passages is much less than that of the cylinder, the flow of air through them takes place at a high velocity, which is conducive to the most efficient flow of heat from the air being compressed into the cooling medium. At all 35 times, even when the piston is in its most remote position from the heat interchanger unit, the plungers project somewhat into the passages and leave open only the annular 40 spaces between their surfaces and the walls of the passages for flow of air. Thus all the air which passes through the cylinder is brought into a close approach to a cylindrical film in contact with the cool walls of 45 the passages, and the flow velocity is made very high, because of the small area of these annular spaces.

As the compression pressure increases, 50 due to progress of the piston, the plungers are farther advanced into the passages, narrowing still further, on account of their tapered formation, the annular entrances to the passages and still further filling the central parts of the passages, leaving less 55 opportunity for air to pass out of direct contact with the surrounding walls.

Thus from the first, the air is brought into 60 intimate contact with the cooled walls of the compression spaces and caused to flow at high velocity in contact with such walls, and as the pressure becomes greater and the 65 conditions occur which tend to raise the temperature of the air, the velocity of the air being compressed is increased and the intimacy of its contact with the enclosing

walls is still further enhanced. At the same time the large number of passages provided for the cooling medium, the close proximity of these passages to the air compression passages, and the presence of a solid mass of 70 material which is a good conductor of heat, around and between all of the passages, enables the heat developed by compression of the air to be rapidly absorbed and carried away.

The chamber f into which the compressed air is delivered may be of as small volume as desired, to the minimum limit of a space which is sufficient to conduct air from the inlet valve to the passages, and to conduct 80 compressed air from the passages to the outlet valve without causing excessive friction. It is to be noted also that one wall of this chamber is the surface of the heat interchanger unit, which is maintained at low 85 temperature, and the outer wall of the chamber may also be provided with a jacket containing a cooling medium, if desired. I am, therefore, able to accomplish the result of compressing air to any desired pressure 90 and of dissipating the heat of compression substantially as fast as such heat is generated, and of delivering air compressed to any pressure desired at a temperature substantially the same as its initial temperature, 95 or even at a lower temperature, in case a refrigerated cooling medium (that is, any medium of which the temperature is enough lower than that of the air for the purpose mentioned) is used. The efficiency of the apparatus and its mechanical simplicity enable me to obtain very great economy in 100 air compression.

In this description I have used the term "air compressor" and terms of similar import in an illustrative and not a limiting sense. The machine or apparatus may be applied for compressing any gases to any desired pressure, or for liquefying air and other gases. I intend to claim and protect 110 the novel characteristics of the apparatus in all uses and for all purposes to which it may be put, and the descriptive terms herein used are to be construed accordingly.

What I claim and desire to secure by Letters Patent is:

1. An apparatus for the purposes set forth comprising a heat interchanger unit constructed as a block of substantially solid heat-conducting material with a set of passages extending in one direction and a separate set of passages extending in a different direction and arranged intermediate of the passages of the first-named set, a chamber enclosing a gas-receiving space connected to one end of said unit in communication with one set of passages therein, a fitting at the opposite end of the unit having provisions for conducting gas to and away from said passages, means for conducting a cooling 125

medium through the passages of the second-named set, and a piston working in said chamber toward and away from the unit.

2. An apparatus for the purposes set forth comprising a heat interchanger unit constructed as a block of substantially solid heat-conducting material with a set of passages extending in one direction and a separate set of passages extending in a different direction and arranged intermediate of the passages of the first-named set, a cylinder enclosing a gas-receiving space connected to one end of said unit in communication with one set of passages therein, a fitting 15 at the opposite end of the unit having provisions for conducting gas to and away from said passages, means for conducting a cooling medium through the passages of the second-named set, a piston working in said 20 cylinder toward and away from the unit, and plungers secured to said piston and projecting toward and into the first-named passages, said plungers being of less transverse dimensions than the passages and being 25 adapted to reciprocate therein.

3. An isothermal air compressor comprising a heat interchanging unit constructed substantially as a solid block having a set of passages extending in one direction and 30 a set of passages extending in the trans-

verse direction, the passages of one set being interposed between passages of another set, and means for compressing air arranged to deliver the air so compressed into the passages of one set, whereby the compressed air 35 is cooled by a cooling medium flowing through the passages of the other set.

4. An isothermal air compressor comprising a heat interchanging unit constructed substantially as a solid block having a set of 40 passages extending in one direction and a set of passages extending in the transverse direction, the passages of one set being interposed between passages of another set, and means for compressing air arranged to deliver the air so compressed into the passages of one set, whereby the compressed air is cooled by a cooling medium flowing through the passages of the other set, combined with core pieces occupying centrally the passages 45 of the first set and arranged to leave annular spaces between their lateral surfaces and the surrounding walls of such passages, whereby the air forced into these passages is caused to flow with substantial velocity in the form 50 of films close to said walls.

In testimony whereof I have affixed my signature.

CECIL W. STANCLIFFE.
